CLAIM

The ornamental design for a picture frame antenna, as shown and described.

DESCRIPTION

FIG. 1 is a perspective view of a picture frame antenna, showing our new design;

FIG. 2 is a back perspective view thereof;

FIG. 3 is a front elevation view thereof;

FIG. 4 is a back elevation view thereof;

FIG. 5 is a right elevation view thereof;

FIG. 6 is a left elevation view thereof;

FIG. 7 is a top plan view thereof;

FIG. 8 is a bottom plan view thereof; and,

FIG. 9 is an exploded perspective view thereof showing an exemplary antenna element in broken lines that may be coupled to an inner surface of the back plate and disposed within an interior defined by the picture frame antenna.

In the drawings, the details shown in broken lines depict environmental subject matter only and form no part of the claimed design.
